UNITED STATES PATENT OFFICE.

ELIZABETH A. MORGAN, OF OMEMEE, NORTH DAKOTA.

STOCKING-SUPPORTER.

1,196,471.

Specification of Letters Patent. Patented Aug. 29, 1916.

Application filed June 30, 1915. Serial No. 37,292.

To all whom it may concern:

Be it known that I, ELIZABETH A. MORGAN, a citizen of the United States, residing at Omemee, in the county of Bottineau and 5 State of North Dakota, have invented certain new and useful Improvements in Stocking-Supporters; and I do hereby declare the following to be a full, clear, and exact description of the invention, such as will enable others skilled in the art to which it 10 appertains to make and use the same.

This invention relates to stocking supporters, and one of the principal objects of the invention is to provide a supporter 15 which will not tear or injure the stocking, and which will be reliable and efficient in use and not liable to become detached to release the stocking from the supporter.

The stocking supporters in common use 20 are very injurious to the stockings owing to the fact that the clasps are liable to start one or more of the threads, especially in silk stockings and said threads will run from the top to the bottom of the stockings, thus injuring the appearance and eventually destroying the stocking.

The object of this invention is to provide a stocking holder which will not injure the stocking, and which will perform its function 25 properly.

The foregoing and other objects may be attained by means of the construction illustrated in the accompanying drawing, in which—

35 Figure 1 is a view in elevation of a stocking supporter made in accordance with this invention, and shown connected through an eyelet at the top of a stocking broken away below the top, Fig. 2 is a front elevation of 40 the supporter disconnected from the stocking and made on a slightly larger scale, and Fig. 3 is a vertical section taken on the line 3—3 of Fig. 1, and made on a larger scale.

Referring to the drawing, the numeral 1 45 designates a stocking and 2 is an eyelet secured near the upper edge of the stocking, said eyelet being formed of metal, celluloid, or said eyelet may be worked in the stocking by button hole stitches, if desired.

50 The numeral 3 designates a fabric tab bent upon itself at 4 and connected together by means of stitches 5. Connected to the lower edge of one of the layers of the tab 3 is a hook, said hook having a rounded bill,

and spaced members 7, said members being 55 curved at 8, and the bill of the hook lying parallel with the tab portion to which it is secured. Connected to the tab 3 adjacent the hook, is a cord loop, said cord loop comprising the two members 9 connected together for a portion of their length, and the two members being separated to form a loop 10. The loop 10 is adapted to pass through the eyelet 2, and to be connected to the hook 6. The outer flap 11 of the tab 3 is provided 60 with a socket member 12 of an ordinary glove fastener, said socket member adapted to engage a ball member 13 secured to the other member of the tab 3, as shown more clearly in Fig. 2. The ball member is connected to a reinforcing piece 14. 65

The tab 3 may be supported by the means of a loop 15 and said loop being supported from a corset or from a waist belt.

From the foregoing it will be obvious that 75 two or more of the supporting devices may be connected to the stocking and the stocking may have a plurality of eyelets or worked button-holes therein.

Various changes may be made in the details of construction without departing from the spirit and scope of the invention as defined in the claim. 80

What is claimed is:—

A stocking supporter comprising a tab, 85 doubled upon itself and stitched adjacent its upper end forming a pair of members the lower end of one member being open, a hook connected to the lower edge of one of the layers of one of the tab members, said hook 90 having a flat bill and an attaching member, said member being flat curved and the bill of the hook lying parallel with the tab portion to which it is secured, a loop connected to the rear of the hook and its free end 95 adapted to be passed through an eyelet of a stocking, the said loop being engaged over said hook for supporting the same, and a ball and socket fastening on the two members of the tab connecting them together, 100 substantially as set forth.

In testimony whereof I affix my signature in presence of two witnesses.

ELIZABETH A. MORGAN.
